Primary Examiner — Steven J Czyz(74) Attorney, Agent, or Firm — Workman NydeggerCLAIM

The ornamental design for a cabinet, as shown and described.

DESCRIPTION

FIG. 1 is a front perspective view of a cabinet showing the new design;

FIG. 2 is a front elevation view thereof showing the sliding door slid to the left of the cabinet;

FIG. 3 is front elevation view thereof, showing the sliding door in an alternate position of use to the right of the cabinet;

FIG. 4 is a back elevation view thereof;

FIG. 5 is a top plan view thereof;

FIG. 6 is a bottom plan view thereof;

FIG. 7 is a right elevation view thereof; and,

FIG. 8 is a left elevation view thereof.

The broken lines shown in the Figures illustrate portions of the cabinet that form no part of the claimed design.
